(57) **CLAIM**

The ornamental design for an operation device for vehicle equipment, as shown and described.

DESCRIPTION

FIG. 1 is a front elevation view of an operation device for vehicle equipment showing our new design;

FIG. 2 is a rear elevation view thereof;

FIG. 3 is a top plan view thereof;

FIG. 4 is a bottom plan view thereof;

FIG. 5 is a left side elevation view thereof;

FIG. 6 is a right side elevation view thereof;

FIG. 7 is a front, bottom, and right side perspective view thereof;

FIG. 8 is a front, top, and left side perspective view thereof; and,

FIG. 9 is a front, top, and left side perspective view thereof, wherein the operation device is shown in use and attached to a vehicle.

The article of the present design relates to an operation device for a vehicle equipment. For example, the operation device may be attached to a predetermined portion of a vehicle, and may be used for remotely operating a vehicle equipment such as a navigation device, an air conditioner, various audio devices or the like. As an example, the operation device may be attached to a console of the vehicle, as shown in FIG. 9. The broken lines shown in the drawings illustrate environmental subject matter of a hand and portions of a vehicle for the operation device for vehicle equipment that forms no part of claimed design.

1 Claim, 5 Drawing Sheets
